UNITED STATES PATENT OFFICE.

ELIJAH F. SPAULDING, OF BROOKLYN, NEW YORK, ASSIGNOR TO ARTEMAS WARD, OF NEW YORK, N. Y.

VENDING-MACHINE.

1,320,505.

Specification of Letters Patent.

Patented Nov. 4, 1919.

Original application filed November 8, 1917, Serial No. 200,861. Divided and this application filed January 28, 1918. Serial No. 214,134.

To all whom it may concern:

Be it known that I, ELIJAH F. SPAULDING, a citizen of the United States, and resident of New York city, borough of Brooklyn, 5 in the county of Kings and State of New York, have invented certain new and useful Improvements in Vending-Machines, of which the following is a specification.

This application is a division in part of 10 my application for patent on vending machines, filed November 8, 1917, Serial No. 200,861.

My invention relates to improvements in coin-controlled vending machines, and has 15 particular reference to means to prevent the entrance of a coin through the coin slot of the machine when devices in the machine are operated for the discharge of an article therefrom.

20 My improvements are illustrated in connection with the class of machines set forth in Letters Patent No. 1,148,807, on vending machines, granted to me August 3, 1915.

My invention comprises novel details of 25 improvement and combinations of parts that will be more fully hereinafter set forth and then pointed out in the claims.

Reference is to be had to the accompanying drawings forming part hereof, 30 wherein,

Figure 1 is a vertical section substantially on the lines 1, 1; in Fig. 4; Fig. 2 is an enlarged vertical section substantially on the line 2, 2, in Fig. 3, illustrating the parts 35 in operated position; Fig. 3 is a plan view illustrating my improvements, parts being removed and part in section; Fig. 4 is a partly broken front elevation of Fig. 3; Fig. 5 is a longitudinal section, parts being re- 40 moved, looking from the rear of the mechanism; Fig. 6 is a detail plan view, partly in section, illustrating the coin receiving devices and the coin extractor; Fig. 7 is an enlarged detail section of part of Fig. 6, 45 and Figs. 8 and 9 are sectional details.

Similar numerals of reference indicate corresponding parts in the several views.

While my improvements relate to means to prevent the insertion of a coin in a slot 50 29 when a corresponding lever 22 is operated to discharge an article 3 from the machine, I have illustrated my improvements in connection with coin controlled mechanism for discharging such articles in

accordance with the disclosure in my afore- 55 said application Serial No. 200,861, but the particular coin controlled devices for operating such lever are not herein separately claimed, as they are claimed in my said application.

In the accompanying drawings, a suitable 60 casing is indicated at 1, in which one or more chutes 2 are provided for the articles 3 to be vended. At the bottom of the chutes are spaced ledges 4 suitably secured to the 65 chutes for the articles 3 to rest on, the rear portions of the chutes being open to permit the passage of the depending projections 5 from weights 6 that rest on the articles and are adapted to slide in the chutes respectively. The forward or delivery portions of 70 the chutes at the lower ends thereof are provided with openings at 2^a through which the lowermost article 3 may be discharged. In front of each opening 2^a is a flap 7 pivotally supported upon the chute at 8 (Figs. 1 and 2), normally pressed by a spring 9 to 75 close in front of the corresponding opening 2^a. The flap 7 is adapted to be pushed outwardly, by an article 3 when the latter is 80 being discharged, and the flap is adapted to swing back in front of the opening normally to prevent the surreptitious extracting of an article from the chute. Rearward swinging of the flap is limited by the chute. The 85 chutes 2 may be fitted in casing 1 singly, or united together for joint removal from the casing in any well-known manner. The rear hinged door 1^a of the casing is adapted 90 to close over the chutes to protect the articles 3 therein, and the door may be fastened shut by a lock in any well-known manner.

Beneath the chutes coin controlled article delivery mechanism is located within casing 1. In the form illustrated said mechanism 95 is carried by a suitable frame 10 that is adapted to be detachably rested upon supports or side brackets 11, shown located along the side walls of casing 1, and having upturned rear lugs 11^a to engage the lower 100 rear corners of frame 10 (Fig. 1). The frame 10 at its upper edges is shown provided with inwardly extending rests 10^a, upon which the corresponding lower corners of the chutes rest, which lower corners of the chutes are shown provided with downward projections 2^b adapted to fit in transverse recesses 10^b respectively in the rests 105

10^a, to detachably retain the chute (Figs. 1 and 3). When the mechanism is to be removed the chute 2 may be lifted off frame 10 and the latter may be pulled out of the casing, and when frame 10 has been replaced in the casing the chute may be replaced and applied upon said frame. At 12 is a transverse shaft shown journaled in the end walls of frame 10, to which shaft a segment-shaped miter gear 13 is suitably secured for rocking said shaft. A coil spring 14 is shown surrounding shaft 12, and one of its ends bears against said gear while its other end bears against the cross bar 10^c of frame 10, which spring serves to return shaft 12 to its normal position after operation. A weight may be substituted for such spring if preferred, substantially in accordance with my aforesaid Letters Patent. A miter gear 15 meshes with gear 13 for operating shaft 12. The gear 15 is secured to a shaft 16 that is journaled in the front wall or cross bar 10^d of frame 10. Shaft 16 projects outwardly from wall or cross bar 10^d and is provided with a handle or finger piece 17 for operating said shaft (Figs. 1 and 2). Casing 1 is shown provided with an opening 1^b through which handle 17 is adapted to pass when frame 10 is placed within or removed from the casing. Shaft 16 is shown provided with a ratchet 18 having a shoulder 18^a adapted to engage a stop 19 on frame 10 to limit rotation of shaft 16 in one direction as influenced by spring 14, whereby to retain shaft 12 in the normal position, and ratchet 18 is shown provided with a stop 18^d to engage the stop 19 to limit manual rotation of shafts 16 and 12 in operating direction (Fig. 4). The ratchet 18 is adapted to retain shafts 16 and 12 in one or more partially operated positions, between the limits of rotation of shaft 16, by means of a dog 20 that is pivotally supported at 21 upon wall or cross bar 10^d as hereinafter explained (Fig. 4).

At 22 are rock levers pivotally supported upon shaft 12, each of which levers corresponds to one of the chutes 2, the levers being spaced apart according to the spacing of the chutes and located below the same. Spacers α are shown on shaft 12 adjacent to levers 22. If the machine is provided with one coin slot one of the levers 22 with devices hereinafter described to operate it will suffice. The levers normally rest against the upper cross bar or wall 10^e of frame 10 (Fig. 1), with their upper portions normally at one side of the vertical plane of the rear of the corresponding chute. The levers are adapted to pass under the corresponding chute to push the lowermost article from the chute through its opening 2^a when the lever is caused to rock forwardly by a coin 23 when it is opposed to the lower projecting portion 22^a of the corresponding

lever. I have shown the upper ends of the levers each provided with an ejector 24, having depending ears 25 pivotally supported upon the corresponding lever 22, the weighted end 24^a of such ejector normally bearing against the rear of its lever 22 and thereby being retained to push article 3 from the chute above. The ears 25 may bear against the sides of the corresponding levers 22 to retain the ejectors from lateral movement. After an ejector has pushed the lower article 3 from a stack of articles in a chute 2, the upper free end of the ejector will slide rearwardly under such lowermost article back to the normal position when lever 22 returns thereto. When the lowest or last article (or, if preferred, next to the last article) of a stack has been ejected, the weight 6 will have descended sufficiently low to cause its projection 5 to be brought opposite the upper projecting end 22^b of lever 22 to prevent said lever from resuming its normal position, as indicated in Fig. 10, whereby such lever cannot be operated again until the weight has been raised, as when a new stack of articles is placed in the corresponding chute with the weight on such articles. When the ejector 24 is moved forwardly to eject an article 3 from the chute, it will cause the corresponding flap 7 to be swung open by the article, and when the article has been fully pushed out of the chute it will drop from under the flap down through passage 27 within the casing to rest upon the exposed support or wall 28 in position for removal (Fig. 2). The support 28, which may be made of any suitable construction, is secured in frame 1 in front of the upper portions of levers 22, and said support is provided with a coin slot 29 corresponding to each lever 22. Beneath each coin slot 29 is a movable slot closer 30 operatively connected with the corresponding lever 22, and so arranged that when such lever is in the normal position (Fig. 1) the closer 30 will be retracted from beneath slot 29 to permit the passage of a coin therethrough, and when lever 22 is swung forwardly, for ejecting an article, the closer 30 will be correspondingly moved forwardly under slot 29 to prevent the entrance of a coin into the machine through said slot until the lever has returned to normal (Fig. 2). The slot closer 30 is shown in the form of a flat plate slidable in a recess or opening 31 at the upper edge portion of a plate 32, which is movably supported within frame 10, as hereinafter explained. The closer 30 is shown provided with a bent lug 30^a movably fitted in a hole 33 in the corresponding lever 22, whereby such closer is detachably connected with the lever. The hook-like lug 30^a may be applied to lever 22 by turning the closer 30 flatwise with respect to lever 22 to pass the free end of the lug through hole 33, 130

and then the closer may be turned at right angles, with the lug in said hole, so that the closer may slide flatwise upon plate 32. I prefer, in the normal position of lever 22 and closer 30 (Fig. 1), that the forward end of the closer shall oppose a stop indicated at 10^d on wall 10^a in Fig. 1, which stop preferably has its corner rounded adjacent the end of the closer, or the forward edge of the closer may be rounded, so that the closer will slide upon said stop when lever 22 is pushed. If an instrument be inserted in slot 29 to engage and push the closer forward to operate lever 22, the closer will be pushed down behind and against said stop 10^d to prevent sliding of the closer and operation of the lever for preventing surreptitious extracting of articles 3 by operating the lever without a coin.

For operating the levers 22 by means of coins I have illustrated the following devices, which pertain to features claimed in my said application Serial No. 200,861. A movable member 34 has spaced arms 34^a located adjacent the inner surfaces of the end walls of frame 10, and mounted upon shaft 12 to swing below the same, which member is operatively connected with said shaft to be rocked therewith. I have shown member 34 provided with a projection 34^b that is operatively connected with a gear 13, as by being fitted in a slot 3 therein (Fig. 1), whereby as said gear is rocked member 34 will be correspondingly rocked. Member 34 has laterally extending spaced projections 35, 36 for each lever 22, adapted to support a coin over or in the corresponding space 37 therebetween within which spaces corresponding lower projections 22^a of corresponding levers 22 may operate. The member 34 is also shown provided with spaced recesses 34^c for the free play of projections 22^a. Upon projection 35 is a stop 38, shown in the form of a screw, for coöperation with one edge of a coin and on the projection 36 is a coin stop 39 opposed to screw 38 adapted to coöperate with the opposite edge of such coin, whereby the latter will be bridged across between the stops 38 and 39. The stop 39 is movably carried by member 34, and is so arranged as to resist thrust of the coin when it is moved with member 34 to operate the corresponding lever 22, and to move independently when the member moves in the opposite direction for releasing the coin. Stop 39 is shown comprising a piece of metal having a base 39^a from which extend outwardly flaring wings or projections 39^b having downwardly beveled edges 39^c to coöperate with a coin, the side edges of the base 39^a also coöoperating with the coin, which base rests upon the projection 36. Said base has a downwardly extending lug 39^d on the rearward side of projection 36, and an upwardly extending lug 39^e that is fitted in the forked lower end of a block 40 secured to the upwardly extending portion of member 34 by screw 41, whereby said stop 39 is supported for free movement upon projection 36 (Figs. 1 and 2). When a coin is entered through a coin slot 29 the coin slides to position between the corresponding screw 38 and the opposing edge of stop 39, in which position the coin will be beneath the projection 22^a and opposing a shoulder 22^c of the lever for pushing the lever to rock it (Figs. 1, 2). Since I have shown a plurality of levers 22, spaced apart, I have shown a movable stop 39 between two spaced screws 38, one side of which stop 39 coöperates with a coin from one slot, and the other side of the stop 39 with a coin from another slot, which coins in turn coöperate with the corresponding stop screws 38, whereby each of the movable stops 39 is adapted to coöperate with two coins. It will be understood however, that if the machine were provided with a single lever 22, a single stop 39 to coöperate with a corresponding single stop 38 would be provided.

In order to guide a coin to operative position between a stop 38 and the adjacent stop 39, and to cause said coin to push corresponding lever 22 when member 34 is operated, I provide a movable coin pusher 42 carried by member 34. Said pusher is provided with lugs 43 at its ends pivotally supported at 44 upon arms 45 projecting laterally from member 34, whereby the pusher 42 is movably carried by and with said member. A coil spring 46 connects member 34 with pusher 42 on one side of the plane of the pivots of the latter, thereby tending to tilt the forward edge of the pusher behind coins on member 34. Normally, however, such edge of the pusher is maintained below the coin, and the pusher serves as a guide for the coin to its position between the stops 38 and 39. For such purpose pusher 42 is shown provided with a projection 47 adapted to engage the wall or cross strip 10^d of frame 10, when the parts are in their normal positions (Fig. 1), to tilt the pusher 42 against the tension of spring 46, and 110 whereby when the pusher is carried along with member 34 when handle 17 is rotated, projection 47 will move away from said wall to permit spring 46 to tilt the pusher behind the coin. To control the tilting of pusher 42 by spring 46 the projection 47 is provided with a projection 48, which projection enters a recess 34^d in member 34 to engage the latter to check the tilting of member 42 by spring 46.

When a coin is passed through a slot 29 it drops into the space 49 between the movable member 32 and the plate or cross strip 10^a, and the coin slides between suitably spaced stops 50 on said plate which guide the coin 130

to the corresponding projecting portion 42^a of the pusher 42. Said portion 42^a normally is retained beneath the coin slot and passage 49 to receive the coin to guide it on the pusher to its seat on member 34 between stops 38 and 39, opposing shoulder 22^c of member 22. Plate 32 is cut away or provided with openings at 32^a coöperative with the corresponding projecting portions 42^a of pusher 42, in such manner that when a coin drops upon the latter it will pass freely beyond member 32.

At a position to one side of or behind the position at which the coin is received between the stops 38, 39 on a member 34, is located a coin extractor, to discharge coins from member 34 after the operation of the corresponding lever 22 by the coin. Said extractor is indicated at 51 and is shown 20 substantially in the form of a cross bar having arms 52 at its ends pivotally supported at 53 upon the end walls of frame 10 to rock. Said extractor is shown provided with upward lugs 51^a normally opposing a coin 25 on member 34, and in the path of the coin, which lug is shown forked at 51^b whereby the projection 22^a of the corresponding lever 22 may play in such fork. The lugs 51^a are also shown slotted at 51^c, whereby if a coin 30 with a string attached be inserted in the machine and pushed with member 34 beyond a lug 51^a, the string will be caught in the slot 51^c to be severed when the string is pulled. The coin extractor 51 is normally 35 retained in such position that a coin on member 34, when the latter is rocked forwardly, will push the extractor and tilt it by engagement of the coin with a corresponding lug 51^a, whereby the coin will ride over such lug 40 and will advance beyond it, and whereby during the return stroke of member 34 the rearward edge of the coin will engage the lug and the latter will dislodge the coin from member 34 for deposit in any suitable 45 receptacle in casing 1. Any suitable spring may be utilized to normally retain extractor 51 in normal position with its lug 51^a in front of the path of a coin carried by member 34. Such a spring is indicated at 50 54 shown attached to frame 1 at 55 and bearing at its end 54^a against extractor 51, said spring normally tending to tilt the extractor rearwardly with the arm 52 bearing against a stop 56 carried by an end wall of frame 10. 55 I have shown extractor 51 provided with a projection or finger 57 that extends forwardly to coöperate with the dog 20 before referred to. Said dog is shown provided with a spring 58 resting upon projection 57, 60 said dog also having an arm 20^a beneath said projection (Fig. 4). When the extractor is in the normal position its projection 57 bears down upon arm 20^a of dog 20 to withdraw the dog from coöperation with ratchet 18, as indicated in dotted lines in

Fig. 4, and so long as there is no coin upon member 34 said ratchet and shaft 16 may be rotated but the levers 22 will not be actuated. When a coin is deposited through slot 29 and rests between the appropriate 70 stops 38, 39, of member 34, and shaft 16 is then rotated, the coin will be carried forward by the pusher 42 into engagement with a lug 51^a of extractor 51, causing the latter to tilt, and thereupon its projection 57 will 75 rise and will push spring 58 upwardly, whereupon dog 20 will be raised into coöperation with a tooth of ratchet 18 to prevent reverse rotation thereof, and whereby reverse movement of member 34 is prevented, 80 requiring continued forward rotation of shaft 16 before the parts can be brought back to normal. As said shaft 16 is continued forwardly the ratchet 18 will pass the dog until the coin passes beyond lug 51^a, 85 whereupon the latter will be released and its spring 54 will return the extractor to normal, whereupon projection 57 will descend to operate upon arm 20^a to withdraw dog 20 from coöperation with ratchet 18, whereby 90 shaft 16, when released by the operator, will return to normal under the influence of spring 14 operating gears 13 and 15, and correspondingly member 34 and pusher 42 will return to normal positions. 95

To prevent tokens that are subject to magnetic attraction from reaching the member 34, if passed through a coin slot, I provide a magnet 59 which is shown projecting inwardly from wall or strip 10^b across space 100 49 (Fig. 3), and spaced from an adjacent stop 50, beneath the corresponding coin slot. When a magnetic token passes from the coin slot between said magnet and stop, the magnet will attract the token to draw it to one 105 side away from the line of descent to the projecting portion 42^a of pusher 42, so that the token may pass through the front space 42^b of said pusher below (Fig. 4), to a passage or way 60 within casing 1, which leads 110 to an outlet 61 from the casing to discharge such tokens and prevent them from operating the mechanism. Passage 60 is shown provided between the front wall of casing 1 and the downwardly converging wall 62 secured within the casing. Since, in the example illustrated, provision is made for a coin slot for corresponding controlling devices, I have shown two magnet poles 59 each spaced below two adjacent coin slots, 115 the magnets being shown carried by a bar 59^a secured by screws 62 on the outside of wall 10^d which is provided with openings 63 for the passage of the magnet poles (Figs. 3 and 4).

Having now described my invention what I claim is:

1. In a vending machine, the combination of a casing having a coin slot, a chute for articles, a lever having means to dis- 130

charge articles from the chute, coin controlled means to actuate said lever, a slot closer operatively connected with the lever to move therewith to obstruct the passage 5 of a coin through the slot when the lever is operated to eject an article and means to obstruct operation of said closer when engaged by an instrument operated through the coin slot whereby to prevent operation 10 of the lever to discharge an article.

2. In a vending machine, the combination of a casing having a coin slot, a chute for articles, a lever having means to discharge articles from the chute, coin controlled means to actuate said lever, a slot closer operatively connected with the lever to move therewith to obstruct the passage 15 of a coin through the slot when the lever is operated to eject an article, means to obstruct operation of said closer when engaged by an instrument operated through the coin slot whereby to prevent operation of the lever to discharge an article and means to retain the lever in operated position to keep 20 the slot closer opposing the slot when a desired number of articles have been discharged from the chute.

3. In a vending machine, the combination of a casing having a coin slot, a chute for 30 articles, a lever having means to discharge articles from the chute, means to actuate said lever, a plate movably connected with the lever, means to guide the plate beneath the slot to oppose the passage of a coin through 35 the slot when the lever is moved to discharge an article from the chute, a stop opposing the plate adjacent the forward side of the coin slot, said stop normally permitting the plate to pass it and shaped 40 to prevent the plate passing it when pressure is applied upon the plate, and means to prevent the return of the lever to retain said plate opposing the slot when a desired number of articles have been discharged from 45 the chute.

4. In a vending machine, the combination of a casing having a coin slot, a chute for 50 articles, a lever having means to discharge articles from the chute, means to actuate said lever, means operated by the lever to

prevent entrance of a coin through said slot when the lever is operated to discharge an article, a stop opposing said means to prevent its operation by an instrument inserted in the coin slot to discharge an article, and 55 means to prevent return movement of the lever from a partially operated position to retain the coin slot obstructed by said slot obstructing means until the completion of the operation of the lever. 60

5. In a vending machine, the combination of a casing having a coin slot, a chute for articles, a lever having means to discharge articles from the chute, means to actuate said lever, a slot closer operatively connected 65 with the lever to move therewith to obstruct the passage of a coin through the slot when the lever is operated to eject an article, a stop opposing said closer to prevent its operation by an instrument inserted in the 70 coin slot, said stop having a beveled edge permitting normal passage of said closer thereover, means to slidably guide the closer toward and from the stop and means to prevent return movement of the lever with the 75 closer from a partially operated position to retain the slot closer obstructing the coin slot until the return of the lever with the closer from a fully operated position.

6. In a vending machine, the combination 80 of a casing having a coin slot, a chute for articles, a lever having means to discharge articles from the chute, coin controlled means to actuate said lever, a slot closer operatively connected with the lever to move 85 therewith to obstruct the passage of a coin through the slot when the lever is operated to eject an article, a stop having a beveled edge in the path of the slot closer permitting the closer to pass over the stop when 90 operated by the lever, and to prevent operation of the lever by the closer to discharge an article.

Signed at New York city, in the county of New York and State of New York this 26th 95 day of January A D., 1918.

ELIJAH F. SPAULDING.
